UNITED STATES PATENT OFFICE.

FREDRICK L. VERMILLION, OF SPRINGFIELD, ILLINOIS.

MACHINE FOR PRINTING PHOTOGRAPHIC NEGATIVES.

1,086,487.

Specification of Letters Patent. Patented Feb. 10, 1914.

Application filed September 3, 1912. Serial No. 718,402.

To all whom it may concern:

Be it known that I, FREDRICK L. VERMILLION, a citizen of the United States, residing at Springfield, in the county of Sangamon and State of Illinois, have invented new and useful Improvements in Machines for Printing Photographic Negatives, of which the following is a specification.

This invention relates to a machine for printing photographic negatives, and particularly contemplates provision of a device of this character wherein negatives of panoramic pictures can be printed by the use of the entire machine, or wherein a plurality of other negatives may be printed at the same time but in different compartments. Heretofore different forms of negatives could not be printed in machines of this nature because of the fact that certain requirements have to be complied with, which requirements differ materially in each case.

The particular object of this invention is to devise a machine wherein, as has been above described, negatives of different types can be printed in the same machine and from the same light.

With the above and other objects in view my invention consists in such details of construction and in the arrangement and combination of parts as will be hereinafter more fully described and specifically pointed out in the appended claims.

In describing my invention in detail, reference will be had to the accompanying drawings wherein like characters denote like or corresponding parts throughout the several views, in which:

Figure 1 is a plan view of my invention, Fig. 2 is a front elevation thereof, Fig. 3 is a sectional view showing the parts in elevation, Fig. 4 is a sectional view taken on line A—A of Fig. 2, and Fig. 5 is a detail view.

In the accompanying drawings wherein is illustrated the preferred form of my invention the numeral 1 designates the supporting structure for the frame work of the machine, which supporting structure consists of a plurality of standards, which have connected with, as clearly shown, a plurality of cross pieces 2. The lower ends of the standards are held rigid in relation to each other through the medium of the members 3 and 4, as clearly shown.

55 Pivotaly mounted upon one of the cross

pieces 2, through the medium of hinges 5, are the door members 6 which are adapted to close the front end of the two compartments shown. A movable partition 7 extends between a pair of the standards 1. Pieces 8 support a platform 9 upon which is mounted at substantially obtuse angles a plurality of lamp sockets 10. By disposing the sockets as shown greater brilliancy may be had from the lights held therein, as will be obvious. For the purpose of reflecting the light upwardly and for the purpose hereinafter set forth, reflectors 11 and 12 are provided which have connection with the platform as shown. A glass plate 13 is mounted above the lights as shown and disposed in a slanting position, upon which may be placed mats for vignetting and tissue paper for softening the light, when such treatment of a negative is required.

For the purpose of supporting the negatives, a plate glass 14 is supported upon arms 15 and has operating thereover spring pressed members 16, composed of two parts hingedly connected at 16', which are carried by plungers 17, as shown. The plungers are hingedly secured to the frame work, as shown at 18, and are provided with handles 19 whereby they may be more easily handled. Coil springs 20 are interposed between the pieces 21 and the members 16 whereby the same are pressed into engagement with glass plate 14, for the purpose hereinafter appearing. I find it advantageous to provide an efficient means for securely holding the plungers in the operative position shown in Fig. 3. This means comprises a bracket 22 which is carried by the frame work of the machine and a pivoted pawl 23 carried by the handle of the plungers. The pawls are adapted to engage the brackets as shown whereby the secure holding of the plungers is effected.

Any suitable electric circuit may be connected with the machine for the purpose of furnishing power to the lights, and I desire it to be understood that I am not limited to any specific form whatsoever.

In the operation of the machine the negatives are disposed upon the plate 14 and the sensitized paper placed thereon. The plungers are then moved in place and the lamps lighted automatically through the medium of the device shown in Fig. 5. Plungers 17, pressing downward on member 23, closes

the electric circuit by making connection between members 23 and 24, thus lighting the lamps.

It will be readily realized that the machine which I have disclosed is very simple in construction and it is thought that the advantages and novel feature of the same will be readily appreciated from the foregoing description.

10 I desire it to be understood that I may make slight changes in the construction and in the arrangement and combination of parts, provided such changes fall within the scope of the subjoined claims.

15 Having thus fully described my invention, what I claim as new and desire to secure by Letters Patent, is:—

1. In a photographic printing apparatus, a frame, a relatively long transparent bed 20 for supporting the negative and sensitized element or elements thereon, a plurality of pressure back devices adapted to close down on and back the bed, a light chamber below

and coextensive with the bed and having reflectors along the side portions curved upwardly toward said bed, lamps disposed between said reflectors and arranged in angular relation with respect to the vertical and in staggered order, and a removable partition for dividing off a portion of said 30 chamber, substantially as described.

2. In a photographic printing apparatus, a frame, a transparent bed for supporting the negative and sensitized element or elements, a pressure back device adapted to 35 close down on and back the bed, a light chamber below the bed having reflectors alongside the side portions thereof curved upwardly toward said bed, and lamps disposed between said reflectors and arranged 40 in angular relation with respect to each other, substantially as described.

FREDRICK L. VERMILLION.
